UNITED STATES PATENT OFFICE.

ARCHIBALD TURNER AND HUGH JAMES TURNER, OF LEICESTER, ENGLAND.

METHOD OF PRODUCING ENDLESS ELASTIC BANDS.

1,312,770.

Specification of Letters Patent.

Patented Aug. 12, 1919.

Application filed October 12, 1916. Serial No. 125,312.

To all whom it may concern:

Be it known that we, ARCHIBALD TURNER and HUGH JAMES TURNER, both subjects of the King of Great Britain, citizens of 5 Leicester, England, residing at Leicester, in the county of Leicester, England, have invented new and useful Improvements in Methods of Producing Endless Elastic Bands, of which the following is a specification.

This invention relates to a new or improved construction of endless elastic band, cord, and the like and to the method of producing the same, and has particular reference to that type of band or cord adapted 15 to withstand considerable tensile strain or to act in the capacity of a shock absorber.

The object of the invention is to produce an endless elastic band capable of resisting wear 20 to a maximum degree and with a minimum liability to collapse as the result of a fracture occurring in its external surface such as take place with solid rubber bodies.

The elastic band constructed according to 25 the present invention comprises a core consisting of a multiplicity or group of thin elastic threads formed from either a single cord of rubber thread wound, reeled, or formed into a series of loops or coils and the 30 ends united or of a number of such cords similarly dealt with or of a multiplicity of endless rubber threads, cords or rings, and a binding medium comprising a cover of one or more plies or layers of textile threads. In 35 cases where a core of this character is formed according to this invention from a single thread or a number of threads by looping or coiling as aforesaid, the ends of the thread or threads is or are united by knotting or tying and the point of union or juncture is inserted between the mass of 40 threads or coils prior to the covering being applied thereto so that no irregularity appears on the surface of the finished bands and in addition the juncture is strengthened 45 thereby in the support it receives from the adjacent threads which surround it.

The multi-thread core thus formed is then stretched or subjected to considerable tensile strain by any convenient means and while in this condition it is covered by the binding medium as for example, by braiding with strong textile threads, linen threads by preference, and when the covering is completed the finished band is removed from the tensioning means and the covering

threads fastened together in any well known manner.

It is essential that the ends of the textile thread covering should overlap sufficiently 60 to prevent any separation or gaping of the ends of the same occurring when the endless band is subsequently submitted to any tensile strain which may be as great as or greater than that at which the core was 65 covered. For maximum efficiency it is advisable that the textile thread covering should be of two or more plies or thicknesses according to the purpose for which the endless band is intended. 70

To enable the invention to be clearly understood a specific example of the method of forming the improved endless elastic band will be described with reference to the diagrammatical views in the accompanying 75 drawing, wherein: Figure 1 is a side view illustrating the method of winding the endless core; Fig. 2 is a front view of the frame and pulleys upon which the core is wound; Fig. 3 shows, in front and side elevation, 80 the device employed for stretching the endless core; Fig. 4 is a side view showing the means for carrying the endless core in a stretched condition while the outer textile covering is being formed about the same; 85 and Fig. 5 shows the endless band after the cover has been completed and the tension released.

The multi-thread core of the endless band may be very conveniently formed by 90 the use of two grooved pulleys 1, 2 which by means of spindles 3 and a frame 4 (Fig. 2) are kept a suitable distance apart. The frame 4 is placed upon the spindle 5 of a beaming machine (Fig. 1) and rotated as 95 indicated by the arrow the rubber thread 6 being mechanically let off by the rollers 7, 8 at the desirable tension and wound about the pulleys 1, 2 forming as represented in the diagram a series of loops or coils 9 extending from one pulley to the other. 100

Before commencing to wind the rubber the first end is tied about the bar 10 of the frame 4 (Fig. 1), then when sufficient rubber thread has been wound upon the pulleys 105 the last end and the first end are tied together as shown at 11 (Fig. 2) thus completing the coils.

The pulleys carrying the wound rubber thread are now removed from the frame 4. 110 for which purpose a device of the character shown in Fig. 3 may conveniently be em-

ployed this comprising a pair of arms 12 pivotally connected at 13 and having at their free extremities notched jaws or bifurcations 14. The jaws are moved toward and from 5 each other by a double threaded screw 15, which engages nuts 16 in the arms. By engaging the spindles 3 by the notched jaws 14 and expanding the arms 12, the spindles 3 may be moved farther apart and removed 10 from the frame 4, then by the same jaw device the said spindles 3 may be placed upon carriers 17 (Fig. 4) whereby the pulleys are supported in such a manner that the coils 9 are maintained in the tensioned condition 15 and on one side pass through a braiding or other machine 18 of a suitable character for forming the covering about said coils.

Prior to forming the textile covering the union or juncture 11 of the rubber thread is 20 pushed in among the mass of threads so as to become buried therein for the aforesaid purpose and then while the machine 19 forms the covering of textile threads about the coiled rubber threads 9 one of the pulleys 25 is slowly rotated as for instance by a chain and chain wheel 20, 21 whereby the whole of the endless cord while maintained in the stretched condition, is drawn through the machine and receives a covering thereon. 30 Any number of covering layers may be formed upon the endless core and in the case of a plurality of such these are formed one upon another by continuing to rotate the pulleys 1, 2 and so drawing the core completely through the machine 19 a number of 35 times. In any case one end of the textile covering 22 (Fig. 5) should overlap the other. For example if the covering 22 commences at the point 23 on the endless core it 40 should be continued right around to somewhere about the point 24.

When covered the band may be removed from the machine by the aid of the jaw device and when removed from the pulleys it 45 contracts and consists of a covered endless band as represented in Fig. 5. The ends 25 of the textile thread may, after the cover has been bound around by a tight thread to prevent it running back, be cut short or 50 stuck down and then covered by a piece of tape or some other suitable material by

wrapping this around the portion of the band where the termination of the textile covering is situated, said tape being secured by stitches or by a suitable solution or adhesive. 55

Instead of making the core 9 from a single cord of rubber thread by coiling the latter and joining its ends as described, the core may be composed of a number of such cords 60 similarly dealt with, that is to say, each cord of rubber thread is wound or coiled and its ends are secured together the whole of such coiled threads combining to constitute a single core. The separate cords of rubber 65 threads may be wound or coiled one after another on the pulleys 1, 2 the ends of each cord being fastened together to form the endless coils.

Or the endless elastic core may be made 70 by aggregating a multiplicity of endless rubber threads, cords or rings which when covered with the binding medium become compacted and bound together.

The specific example herein described is 75 not to be regarded as binding as it will be obvious that means and devices other than those referred to may be employed for carrying out the methods of winding the core and covering the same while it is main- 80 tained in a stretched condition.

What we claim then is:—

The method of producing an endless elastic band of the kind herein described, which consists in first forming an endless uniformly tensioned elastic core by winding under tension a cord of elastic thread into a multiplicity of coils, joining the ends of the elastic cord, transferring said core while maintained under tension to a covering device, maintaining the core under tension in said device and covering the same with a binding medium of textile threads. 85

In testimony whereof we have signed our names to this specification in the presence of 95 two subscribing witnesses.

ARCHIBALD TURNER,
HUGH JAMES TURNER.
